UNITED STATES PATENT OFFICE

FRANCIS LEE STUART, OF NEW YORK, N. Y.

CONVEYING APPARATUS.

1,346,990.

Spécification of Letters Patent. Patented July 20, 1920.

Application filed August 15, 1919. Serial No. 317,680.

To all whom it may concern:

Be it known that I, FRANCIS LEE STUART, a citizen of the United States, residing in New York city, county and State of New York, have invented certain new and useful Improvements in Conveying Apparatus, of which the following is a specification.

This invention relates to apparatus for conveying material such as coal or ore from bins or other similar places of storage to barges, cars, or other conveyers or receivers, and particularly to a storage system in which a series of bins is employed to store material and supply it to apparatus which 15 delivers it to barges or other carriers adjacent the bins.

The particular object of my present invention is to provide means whereby a single delivery apparatus may transfer and 20 deliver material without breakage from a long series of bins to barges or other carriers located at various places adjacent the series of bins.

In carrying out my invention, I provide 25 a series of bins having suitably controlled gates, and on a track running parallel with the bins I support an apparatus which receives material from the bins and delivers it to carriers. The apparatus as a whole is 30 movable on the track so as to receive from any one of the bins in the series, and it is so constructed that it may receive and deliver in any desired vertical or horizontal plane to accommodate particular conditions.

35 In the accompanying drawings:—

Figure 1 shows diagrammatically an end elevation of apparatus embodying my improvements.

Fig. 2 is a plan view of the apparatus 40 shown in Fig. 1.

Fig. 3 is a side elevation of the apparatus, showing its relation with the bins and indicating, by dotted lines, various adjustments of the receiving and delivering parts 45 of the apparatus.

Fig. 4 is a plan view of part of the mechanism shown in Fig. 3.

Fig. 5 is a side elevation of combined receiving and delivering apparatus wherein 50 provision is made for adjusting the conveyers longitudinally or endwise and also about vertical and horizontal axes.

Fig. 6 is a plan view of part of the mechanism shown in Fig. 5.

55 Figs. 7 and 8 are on an enlarged scale.

Fig. 7 illustrates in section details of the mechanism shown in Figs. 5 and 6.

Fig. 8 shows a vertical section on the line 8—8 of Fig. 7.

Referring to Figs. 1 and 2, which show 60 the apparatus diagrammatically, A indicates a series of bins having hopper bottoms a and mounted on supporting frames a' which hold the bins in elevated positions. B indicates a track on the pier C at the foot 65 of the bins and parallel with the series. On this track is supported my improved receiving and delivering apparatus in general comprising a truck D, a delivery conveyor E, and a conveyer F which receives 70 material from the bins and transfer it to the delivery conveyer which deposits the material on barges X or other carriers. It will be understood that each bin or hopper is provided with a suitably controlled gate and 75 by moving the apparatus on the track B to a position opposite any one of the bins material may be taken therefrom and delivered to the barge lying alongside the pier or to cars on adjacent tracks. It will be observed 80 that the receiving conveyer F is so mounted that it may be moved away from the supporting structure of the bins when it is desired to shift the apparatus from one bin to another. It will also be observed that 85 the delivery conveyer is so mounted that it may deliver in any plane to trim or properly load a carrier and to prevent breakage of the material by long falls thereof.

Figs. 3 and 4 show the apparatus more in 90 detail. As there shown, the delivery conveyer E comprises a boom e, in which is mounted a conveyer belt e', operated by a motor e². The boom is mounted to turn about a horizontal axis in a frame H, on a 95 turntable J, supported by the truck D. K indicates a motor for turning the conveyer E about a vertical axis, and K' a motor for turning it about a horizontal axis. K² shows motors for driving the truck. 100

The receiving conveyer F comprises a casing f within which is mounted a conveyer belt f'. The casing is supported on a frame L, mounted on a turntable M, on top of the frame H which supports the delivery conveyer. The casing f is adjustable endwise in the frame L on rollers l, in the manner indicated by dotted lines so that it may be withdrawn from the supporting structure 105 of the bins when it is desired to shift the 110

apparatus from one bin to another. When in operating position the conveyer F receives material from a bin and delivers it through a suitable hopper N to the delivery 5 conveyor E which deposits it wherever required.

It will be observed that there is a turntable between the two conveyers E and F so that one may be turned about a vertical axis 10 without moving the other. This is an important feature inasmuch as the receiving conveyer should not be turned when receiving material from a bin. The receiving conveyer may, however, be turned about a vertical axis in the manner indicated in Fig. 2 15 so as to clear the bin structure and the delivery conveyer E, as before stated, may be turned about vertical and horizontal axes to deliver to any part of a boat or other carrier with a minimum amount of fall for the material and thus avoid undue breakage.

The receiving conveyer may be independently operated by any suitable motor mechanism.

25 Figs. 5 and 6 show a modified form of the apparatus in which provision is made for giving to the delivery conveyer a longitudinal or endwise adjustment in addition to its adjustment about vertical and horizontal 30 axes and to the receiving conveyer adjustment both endwise and about vertical and horizontal axes.

Figs. 7 and 8 show on an enlarged scale details of the apparatus illustrated in Figs. 35 5 and 6. Some parts of the mechanism shown in Figs. 5 to 8 are similar to those shown in Figs. 1 to 4 and they are similarly lettered. In this case, however, the delivery conveyer is mounted in a cradle O and is 40 adjustable endwise therein by means of a motor O'. The cradle is pivoted at q to the frame H to turn about a horizontal axis and the frame moves with the turntable J about a vertical axis. In this way the delivery 45 conveyer may be adjusted to any desired extent longitudinally and about vertical and horizontal axes to receive and deliver in any desired plane.

The receiving conveyer F is mounted in a 50 cradle R, pivoted at r to a frame S to turn about a horizontal axis, and the frame S is supported on the turntable M, and turns about a vertical axis. The conveyer F may be moved longitudinally in the cradle by 55 means of a motor T and the cradle may be moved about its horizontal axis r by a motor U. The frame S is moved about a vertical axis by a motor U.

The conveyer belt V of the receiving 60 conveyer receives material from a chute a^2 connected with the hopper a of a bin and provided with a gate a^3 . The belt V is formed with a tripper v and passes over rollers v' , v^2 which are driven by a motor V' . The 65 tripper delivers to a hopper W which con-

nects with two chutes W' , W^2 in turn delivering to a hopper Y which discharges onto the delivery conveyer E.

An apparatus thus constructed is capable of all the adjustments required in various 70 conditions. The apparatus as a whole can be moved from one bin to another throughout the series so as to receive material from bins containing material or to deliver to barges or other carriers located at any point 75 within range of the bins. The receiving conveyer may be moved into receiving position under various gates and it may be withdrawn from the bin-supporting structure so that the apparatus may be moved along the 80 track without obstruction. The receiving conveyer may be also adjusted about both vertical and horizontal axes to any desired extent, and these operations may be performed by motor mechanism mounted on 85 the apparatus.

The delivery conveyer is also constructed to have all the required adjustments. It may be adjusted endwise or crosswise of the track so as to deliver material to barges or 90 carriers located at varying distances from the track and also to trim or load different parts of a vessel or carrier being loaded. In like manner its delivery end may be adjusted vertically so as to deliver material 95 close to the receiver and thus prevent breakage by a long fall. Furthermore, it may be adjusted in a horizontal plane so as to load or trim different parts of the carrier.

While I have shown and described a 100 simple and efficient apparatus embodying my improvements it will be understood that some parts of my invention may be embodied in apparatus differing in details of construction from those shown and above 105 described. The subject matter of my invention deemed novel is defined in the claims.

I claim as my invention:—

1. The combination with a series of bins, 110 of a truck mounted to move from bin to bin, a boom conveyer mounted on the truck to turn about both vertical and horizontal axes and which discharges material at its end remote from the truck in any desired vertical or horizontal plane, an endwise adjustable belt conveyer receiving material from the bins, and discharging onto the boom conveyer; and a frame in which said belt conveyer is mounted and which is supported by the truck above a receiving portion of the boom conveyer above the truck and remotely located from the outer or discharging end of the boom.

2. The combination with a series of bins, 125 of a truck mounted to move from bin to bin, a boom conveyer mounted on the truck to turn about both vertical and horizontal axes and which discharges material at its end remote from the truck in any desired ver- 130

- tical or horizontal plane, an endwise adjustable belt conveyer receiving material from the bins and discharging onto the boom conveyer, and a frame in which said belt is 5 mounted and which is supported by the truck above a receiving portion of the boom conveyer remote from its discharge end and which is mounted to move about both vertical and horizontal axes.
- 10 3. The combination with a series of bins, of a truck mounted to move from bin to bin, a boom conveyer mounted on the truck to turn about both vertical and horizontal axes and discharging at its outer end, an endwise 15 adjustable conveyer, a frame in which it is mounted and which is supported by the truck above the boom conveyer, said end-
- wise adjustable conveyer being constructed to deliver to the boom conveyer in a fixed vertical plane relatively to the supporting truck substantially as described.
4. The combination of a truck, a turntable thereon, a frame mounted on the turntable, a boom conveyer mounted in said frame to turn about a horizontal axis, means 25 for adjusting said boom conveyer endwise in the frame, a turntable on said frame, a receiving conveyer provided with a tripper delivering to the boom conveyer, and means 30 for supporting said receiving conveyer on said last mentioned turntable.

In testimony whereof I have hereunto
subscribed my name.

FRANCIS LEE STUART.
